Inventor
John L. Tyler

By Townsend & Townsend
Attorney

UNITED STATES PATENT OFFICE.

JOHN L. TYLER, OF GADSDEN, ALABAMA.

SHOE COUNTER.

Application filed April 22, 1925. Serial No. 24,952.

To all whom it may concern:

Be it known that I, JOHN L. TYLER, a citizen of the United States, residing at Gadsden, in the county of Etowah and State of Alabama, have invented certain new and useful improvements in Shoe Counters, of which the following is a specification.

My invention relates to improvements in shoe-construction and particularly to an improved shoe counter. The primary object of the invention is the provision of a metallic counter, and a metallic counter cover adapted to be disposed in a shoe so that durability and flexibility are provided at the heel of the shoe.

Another object of the invention is the provision of a novel form of counter stiffener comprising a counter having a certain degree of inherent flexibility.

The further object of the invention is to provide a counter cover which may be molded or pressed to the contour of the shoe, being constructed of a material which will prevent running down of the shoe heel.

With these objects in view, and such others as will be apparent from the description, the invention resides in the novel construction, combination and arrangement of parts, hereinafter described and claimed and illustrated in the accompanying drawings, of which:

Figure 1 is a vertical section through the heel portion of a shoe equipped with the invention;

Figure 2 is a perspective of my improved counter; and

Figure 3 is a perspective of my improved counter cover.

The invention in detail comprises a shoe counter, 10, cut from a blank of thin, somewhat resilient metal, to conform to the outline of the rear of a heel. The counter thus formed is substantially of horse-shoe formation having its top edge curving gradually downward at the sides, 11, to the forward end of the counter. The bottom of the counter is inturned to form an anchoring ledge which is serrated or scalloped to provide a plurality of inturned lateral flanges, 12, each of which is provided with a fastening nail aperture, 13.

The counter cover, 14, is molded or pressed from a blank of heavier metal, and conforms in outline and shape substantially to the counter, 10, except that the counter may be nested therein to bind a portion of the

upper between the two members. The counter cover, 14, is provided at its bottom with an inturned flange, 15, extending entirely there around, which flange is provided with a spaced series of nail holes, 16, which holes are adapted to register with the nail holes, 13, in the base flanges of the counter, 10, when assembled.

In application, a portion of the shoe leather comprising the heel upper, 17, is laid within the counter cover, 14, covering the base flange, 15. The counter is then inserted into nesting relation within the counter cover, and owing to the configuration of the two members the leather upper, 17, will be securely clamped between the two.

In application to the shoe sole, the base flange, 12, and, 15, of the counter and counter cover respectively with the upper clamped therebetween, are applied so that they extend internally of the sole at the rear of the shoe and between certain layers thereof such as, 18, and, 19. When the heel lift, 20, is applied, the fastening nails, 21, are driven down through the registering nail holes, 13, and, 16, into the body of the heel to secure the parts in assembled relation. In the illustration no outer covering for the counter cover, 14, has been shown, as any such may be applied as desired, such outer facing forming no part of the present invention.

By reason of the inherent flexibility residing in the counter, 10, the walls thereof are permitted to give slightly, yielding to the stresses encountered when the shoe is in service. The cover, 14, being of a heavier material, is stiffer and more durable, considerably reinforcing the heel portion of the shoe and preventing the shoe from running down at the back.

While I have illustrated and described certain details and material entering into the construction of the invention, I desire it to be understood that the invention is not to be limited thereby, but that any desired changes and modifications may be made in such details as will fall within the scope of the invention as claimed.

I claim:

1. In a shoe counter, a cover member adapted to be disposed at the rear of a shoe above a heel, and an internal member of substantially the configuration of the cover member adapted to nest within said cover member independent of said cover member to clamp a portion of a shoe upper therebe-

105

110

tween and for securing said members in assembled relation in a shoe.

2. A shoe counter construction comprising the combination with a metallic counter shaped to conform to the heel of a shoe, of a metallic counter cover shaped to the configuration of said counter and adapted to be applied thereover, said cover being pro-

vided with a base flange whereby a portion of a shoe upper may be clamped between 10 said counter and cover with said counter being disposed in nested relation within said cover.

In testimony whereof I have affixed my signature.

JOHN L. TYLER.
